(57) **CLAIM**

The ornamental design for a brazier heater, as shown and described.

DESCRIPTION

FIG. 1 is a top, front and right side perspective view of a brazier heater showing our new design;

FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a top, front and right side perspective view showing the brazier heater in an open state.

The broken lines in the drawings illustrate portions of the brazier heater which form no part of the claimed design.
